(57) **CLAIM**

The ornamental design for a multi-purpose flashlight, as shown and described.

DESCRIPTION

FIG. 1 is a perspective view showing my new design for a multi-purpose flashlight;
 FIG. 2 is a front view thereof;
 FIG. 3 is a bottom thereof;
 FIG. 4 is a rear view thereof;
 FIG. 5 is a top view thereof;
 FIG. 6 is a side view thereof; and,
 FIG. 7 is a perspective view of a second embodiment of my new design for a multi-purpose flashlight.

The broken lines in the drawing figures are for illustrative purposes only and do not form a part of the claimed design.

1 Claim, 5 Drawing Sheets**FIG. 1.**

FIG. 2.

FIG. 3.

FIG. 4.

FIG. 5.

FIG. 6.

FIG. 7.
